UNITED STATES PATENT OFFICE.

HENRY KOCH, OF JAMAICA, NEW YORK, ASSIGNOR TO DICTOGRAPH PRODUCTS CORPORATION, A CORPORATION OF VIRGINIA.

SECTIONAL SWITCHBOARD FRAME.

Application filed June 17, 1921, Serial No. 478,454. Renewed August 12, 1922. Serial No. 581,492.

To all whom it may concern:

Be it known that I, HENRY KOCH, a citizen of the United States, residing at Jamaica, in the county of Queens and State 5 of New York, have invented certain new and useful Improvements in Sectional Switchboard Frames, of which the following is a full, clear, and exact description.

This invention relates to sectional switchboard constructions for telephonic apparatus and has for an object to provide a frame construction which can be easily and quickly assembled, which is simple, rigid and inexpensive, the parts of which may be 10 stamped from sheet material, and which parts will have a maximum possible standardization so as to reduce to a minimum the number of dies and special parts required for various sizes of switchboards.

20 Other objects and advantages will be apparent from the following description and the novel features of the invention will be particularly pointed out in claims.

In the drawing:

25 Fig. 1 is an inside elevation of a frame constructed in accordance with this invention;

Fig. 2 is an end elevation of the same.

The invention is particularly intended for 30 application to the switchboards of stations devised for intercommunicating telephone systems, and the illustrated embodiment is adapted for that purpose.

Key panels 1 which support the switch 35 keys (not shown) are channel-shaped with the arms 2 of the channels extending horizontally or lengthwise of the switchboard, and having a length corresponding to a given size of switchboard. End plates 3 of 40 sheet metal are provided at their upper and lower edges and adjacent the forward edge corners with inturned tongues or lugs 4 which extend within and parallel with the arms of the channels of the key plates and 45 are secured thereto by screws 5. Each end plate is also provided with lugs 6 struck inwardly in the same plane which form a ledge on the inner face. A switch supporting plate 7 extends between each pair of end 50 plates that are connected to a key panel and rests upon the ledges formed by the lugs 6. A tongue or lug 8 is struck out of the face of each end plate and bent over upon the switch supporting plate 7 to form with the 55 ledges a groove in which the plate 7 may

slide and be held against upward movement. Screws 9 secure the tongues 8 to the ends of the plates 7 to hold the latter securely in place upon the ledges and to prevent separation of the opposite end plates. Spaced 60 tongues or lugs 10 extending downwardly from the lower edge of each end plate are offset inwardly at their juncture with the body of the plate an amount approximately equal to the thickness of the plate, and then 65 extend parallel therewith so as to abut the inner face of a lower end plate, and screws 11 secure these tongues or lugs upon the upper ends to the next lower end plates.

A transmitter and coil board 12 is secured 70 by screws 13 to tongues 14 that extend from the forward edge of an upper frame 15. The upper frame comprises two angular end members which are connected at their upper faces by a plate 16 having a length suitable 75 for any given size of switchboard. The upper frame is coupled to the upper edge of the uppermost end plates by coupling plates 17 and screws 18. The end plates are each provided with apertures 19, 20, 21, 22 80 and 23 to facilitate the assembly of parts to be supported by the frame, and each end plate has the necessary apertures for the reception of screws 11 and 18 so that the end plates can be built up by superposing as 85 many sections as desired from standard parts. A strip 24 may be secured to the bottom arm of the bottom panel by screws 25 and serves as a support for some of the necessary switchboard parts. Tongues 26 90 may extend inwardly from each end plate and support a strip (not shown) that carries cable terminals.

It will be seen that with this construction, the switchboard can be made in various sizes 95 and mainly with standard parts. The key panels, board 12, strip 24 and plates 7 and 16 can be cut to correspond with different sizes and the end frames and upper frame 15 can be used in all sizes of switchboards, 100 so that a minimum number of dies and special parts will be necessary. Practically the entire frame can be made by stamping from sheet material so that the expense is low. The parts are relatively simple, and 105 easily assembled, and when assembled the frame is very rigid. The end plates and key panels can be superposed to provide the desired number of key panels of any length. It is believed that the manner of assembly 110

will be understood from the detailed description without further explanation.

It will be obvious that various changes in the details and arrangements of parts herein described and illustrated may be made within the principle and scope of the invention.

I claim:

1. In a sectional switchboard construction for telephonic apparatus, a unit comprising 10 a key panel having a channel shape, end plates having inturned lugs attached to the arms of the channel, said end plates also having a plurality of struck-out projections in the same plane to form ledges, a switch supporting plate adapted to fit between the end plates and rest upon the ledges, lugs struck from the end plates and overlying the switch supporting plate to hold the latter against the ledges but permitting sliding movement 15 20 25 30 35 40 45 50 55 60 65 70 75 80 85 90 95 100 105 110 115 120 125 130 in a plane parallel with the ledges and means removably inter-engaging with the last named lugs and switch supporting plate for preventing sliding movement of the latter upon the ledges.
2. In a sectional switchboard construction for telephonic apparatus, a unit comprising a key panel having a channel shape, end plates having inturned lugs attached to the arms of the channel, said end plates also having a plurality of struckout projections in the same plane to form ledges, a switch supporting plate adapted to fit between the end plates and rest upon the ledges, and lugs struck from the end plates and overlying the switch supporting plate to hold the latter against the ledges but permitting sliding movement in a plane parallel with the ledges, and means removably inter-engaging with the last named lugs and switch supporting plate for preventing sliding movement of the latter upon the ledges, each end plate having depending lugs for engagement with the corresponding end plate of a lower unit.
3. In a sectional switchboard construction for telephonic apparatus, a unit comprising a key panel having a channel shape, end plates having inturned lugs attached to the arms of the channel, said end plates also having a plurality of struck-out projections in the same plane to form ledges, a switch supporting plate adapted to fit between the end plates and rest upon the ledges, and lugs struck from the end plates and overlying the switch supporting plate to hold the latter against the ledges but permitting sliding movement in a plane parallel with the ledges, and means removably inter-engaging with the last named lugs and switch supporting plate for preventing sliding movement of the latter upon the ledges, each end plate having depending lugs offset laterally an amount equal to the thickness of the plates for engaging with the sides faces of a lower unit.
4. In a sectional switchboard construction

for telephonic apparatus, a unit comprising a key panel, end plates having inturned lugs for attachment to the panel, said end plates also having struck-out projections on their inner faces for forming ledges, a switch supporting plate resting and sliding upon the ledges, said end plates having struck out lugs for holding the switch supporting plate against the ledges but permitting sliding movement thereon, and fastening means between the switch supporting plate and the lugs for preventing sliding movement of the former with respect to the latter.

5. In a sectional switchboard construction for telephonic apparatus, a unit comprising a key panel, end plates, means for attaching the panel to the end plates, each end plate having on its inner face struck out projections in different planes, a switch supporting plate disposed between the end plates with its ends in the space between the projections in different planes, and means for attaching the switch supporting plate to the end plates.

6. In a sectional switchboard construction for telephonic apparatus, a unit comprising a key panel, end plates, means for attaching the panel to the end plates, each end plate having on its inner face struck out projections in different planes, a switch supporting plate disposed between the end plates with its ends in the space between the projections in different planes, and means for attaching the switch supporting plate to the end plates, each end plate having extending lugs for engagement with the corresponding end plate of a lower unit.

7. In a sectional switchboard construction for telephonic apparatus, a unit comprising a key panel, end plates, means for attaching the panel to the end plates, each end plate having on its inner face struck out projections in different planes, a switch supporting plate disposed between the end plates with its ends in the space between the projections in different planes, and means for attaching the switch supporting plate to the end plates, each end plate having depending lugs with terminals offset laterally an amount approximately equal to the thickness of the end plates for engaging with the side faces of a lower unit when superposed thereon in a multi-panel construction.

8. In a sectional switchboard construction for telephonic apparatus, a unit comprising a key panel, end plates having inturned lugs for attachment to the panel, said end plates also having struck-out projections on their inner faces for forming ledges, a switch supporting plate resting and sliding upon the ledges, said end plates having struck over lugs for holding the switch supporting plate against the ledges but permitting sliding movement thereon, and fastening means between the switch supporting plate and the

- lugs for preventing sliding movement of the former with respect to the latter, each end plate having extending lugs for engagement with the corresponding end plate of a lower unit.
9. In a sectional switchboard construction for telephonic apparatus, a unit comprising a key panel having a channel shape with the arms of the channel extending horizontally and rearwardly from the face thereof, end plates having inturned horizontally disposed lugs with their faces abutting the faces of the arms of the panel channel, means for securing the lugs to the arms of the channel, and a switch supporting plate disposed between the end plates, said end plates having struck out portions extending from their inner faces for supporting the ends of the switch supporting plate.
10. In a sectional switchboard construction for telephonic apparatus, a unit comprising a key panel having a channel shape with the arms of the channel extending horizontally and rearwardly from the face thereof, end plates having inturned horizontally disposed lugs with their faces abutting the faces of the arms of the panel channel, means for securing the lugs to the arms of the channel, and a switch supporting plate disposed between the end plates, said end plates having struck out portions extending from their inner faces for supporting the ends of the switch supporting plate.
11. In a sectional switchboard construction for telephonic apparatus, a unit comprising a key panel having a channel shape with the arms of the channel extending horizontally and rearwardly from the face thereof, end plates having inturned horizontally disposed lugs with their faces abutting the faces of the arms of the panel channel, means for securing the lugs to the arms of the channel, and a switch supporting plate disposed between the end plates, said end plates having struck out portions extending from their inner faces for supporting the ends of the switch supporting plate, each end plate having extending lugs for engagement with the corresponding end plate of a lower unit.
12. In a sectional switchboard construction for telephonic apparatus, end frame plates each having inwardly bent integral lugs for attachment to a key panel, struck-out lugs upon the inner faces to form ledges for receiving and mounting a switch supporting plate, and a struck-out tongue extending from the inner face in spaced relation to the ledges for overhanging the switch supporting plate.
13. In a sectional switchboard construction for telephonic apparatus, end frame plates each having inwardly bent integral lugs for attachment to a key panel, struck-out lugs upon the inner faces to form ledges for receiving and mounting a switch supporting plate, a struck-out tongue extending from the inner face in spaced relation to the ledges for overhanging the switch supporting plate, and vertically extending lugs for connecting each end plate to an adjacent end plate in multi-panel construction.
14. In a sectional switchboard construction for telephonic apparatus, end frame plates each having inwardly bent integral lugs for attachment to a key panel, struck-out lugs upon the inner faces to form ledges for receiving and mounting a switch supporting plate, a struck-out tongue extending from the inner face in spaced relation to the ledges for overhanging the switch supporting plate, and vertically extending integral lugs offset with respect to the body of the end plate an amount approximately equal to the thickness of the end plate for connecting each end plate to an adjacent end plate in multi-panel construction.

In witness whereof, I hereunto subscribe my signature.

HENRY KOCH.
